UNITED STATES PATENT OFFICE.

KAEMON KUROSE, OF SEATTLE, WASHINGTON.

AEROPLANE.

1,291,679.

Specification of Letters Patent. Patented Jan. 14, 1919.

Application filed May 12, 1916. Serial No. 97,120.

To all whom it may concern:

Be it known that I, KAEMON KUROSE, a citizen of Japan, residing at Seattle, in the county of King, State of Washington, have 5 invented certain new and useful Improvements in Aeroplanes; and I do hereby declare the following to be a full, clear, and exact description of the invention, such as will enable others skilled in the art to which 10 it appertains to make and use the same.

This invention relates to a hydro-aeroplane.

An object of the invention resides in the provision of a machine which is so constructed that it may rise from the ground 15 after an exceedingly short glide.

A further object of the invention resides in so constructing the device that it may be easily and readily controlled by the operator.

A further object of the invention resides 20 in the provision of floats which are utilized as gasoline containers.

With these and other objects in view, such as will appear as my description progresses, my invention comprises the combination and 25 arrangement of parts as set forth in and falling within the scope of the appended claims.

In the drawing:

Figure 1 is a fragmental plan view of a machine constructed in accordance with my 30 invention;

Fig. 2 is a fragmental front elevation;

Fig. 3 is a side elevation.

Fig. 4 is a detail of the joint for the tail piece, showing the same in elevation and 35 section;

Fig. 5 is a fragmental detail showing the manner in which the propeller is guided;

Fig. 6 is a fragmental detail of the controlling means for the propeller, and

Fig. 7 is an elevational view of the driving gears.

The embodiment of the invention shown in the drawings includes a pair of wings or planes which include frames 2 having covering material 1 thereon. These frames 2 are provided with sleeves 53 which are slidably mounted on circular frames 5, which frames are mounted parallel to each other and are braced by suitable braces 14 and 15, the latter extending horizontally and the former vertically. These planes are braced by suitable wires 3 and 13 which extend from the sides of the frames 2, at 13', and pass slidably through eyes 6 which are carried by the 55 circular frames 5. It will thus be seen that the angles of the planes with relation to the

horizontal is capable of the small adjustment necessary and that irrespective of the positions of the planes they will be braced by the wires 3 as the latter will slide through 60 the eyes 6 when the planes are adjusted.

Extending rearwardly from the upper and lower ends of the frames 5 are arcuate bars 7 which are attached to the frames 5, at 7', and carry a supporting member 17, which member includes a horizontal bar 29. A plate 25 is secured to this horizontal bar 29 and a second plate 24 is mounted on the first plate, rotatably, by means of a bolt 26 which extends concentrically through the plates. 70 The plate 24 carries a block 22, which block is secured to the plate 24 by rivets 27 and to which block an arm 28 is pivoted, which arm is at its other end connected to a tail 9. The tail may therefore have universal movement 75 on its supporting member.

In order that the tail may be raised or lowered, I have secured wire controlling members 46 to the tail, at 10, which controlling members extend through eyes 10' on the frame of the machine and are connected to a controlling lever 43 which is mounted adjacent the seat of the operator as will later appear. In order that the lateral movement of the tail may be effected, I have connected wire controlling members 47 to the tail, at 47', which controlling members extend through suitable guide eyes 10' on the frame and are connected to the shaft of a steering wheel 42. This wheel 42 is mounted on a frame 31, which frame is swung pivotally between the members 16 on the shaft 16' and which frame carries the operator's seat 17'. It is by this frame that the lever 43 is carried. 95

Extending between the sleeves 53 is a brace 53' through which a propeller shaft 11 extends, on the end of which shaft a suitable propeller 4 is secured. This propeller shaft extends rearwardly and is provided with a gear 35 which meshes with a beveled gear 34 which is mounted on a stub shaft 32 carried by the frame 31. The periphery of this gear 34 is provided with a worm gear 33 with which a worm 33' intermeshes, which worm is connected directly to the shaft of the motor 41. This motor is carried by the frame 31. A sleeve 12 encircles the shaft 11 and connected to this sleeve, at 48, is a link 45 which is connected at its other end to a lever 49. This lever 49 is pivoted, at 52, to a quadrant rack 50, on which rack

is mounted a frame 31 and with which a spring pressed pawl 51 coöperates to maintain the lever 49 in any of its adjusted positions. It will thus be seen that when the 5 planes are adjusted the propeller shaft and propeller will be adjusted at the same time but the drive gear 34 and the frame 31 which carries the operator's seat, the motor and controlling levers will remain in their initial or horizontal positions owing to the 10 pivotal connection of the frame 31 with the members 16.

In order that the machine may be supported on the water I have provided the 15 same with a pair of floats 19 which are hollow and are adapted to contain the gasolene which may be fed to the engine in any suitable manner. Shoes 20 are suspended from these floats 19 by means of springs 21 so 20 that the shock of landing will be absorbed.

From the foregoing description it will be seen that I have provided an aeroplane in which the planes may be shifted and in which the position of the propeller will be 25 changed simultaneously with the changing of the planes. Furthermore, I have provided a tail which is universally mounted at the rear of the machine and which in conjunction with the planes will aid the machine in rising. Furthermore, I have provided simple mechanisms for adjusting the 30 planes and tail, which means may be controlled by the operator.

While I have illustrated and described a 35 particular embodiment of my invention, it has merely been for the sake of convenience and I do not wish to be limited to that particular embodiment as it is obvious that numerous changes may be made in the details 40 of construction without departing from the spirit of the invention or exceeding the scope of the appended claims.

What I claim is:

1. In an aeroplane, the combination with a continuous circular frame, adjustable 45 planes carried by the frame and adapted for circumferential movement thereof, means for moving the planes circumferentially of the circular frame, a supplemental frame pivotally carried by the circular frame at the axis 50 thereof, a propeller supported by said circular frame and adjustable circumferentially thereof, and means carried by the supplemental frame for adjusting the said planes and the propeller circumferentially of the 55 circular frame.

2. In an aeroplane the combination with a frame comprising a pair of spaced continuous circular members connected by means of transversely extending braces, a plurality of planes, means carried by the planes and engaging the circular frames to provide for adjustment of the planes circumferentially of the circular frames, rigid braces connecting the opposite sides of the circular 65 frames, a supplemental frame carried by said rigid braces near the axis of the circular members, a propeller, a shaft for said propeller extending radially of the circular frames, means for connecting the circular 70 frames and adapted to support the propeller shaft, means carried by the supplemental frame for adjusting the propeller shaft, means carried by the supplemental frame for adjusting the propeller shaft, and means carried by the supplemental frame for adjusting the planes. 75

In testimony whereof, I affix my signature, in the presence of two witnesses.

KAEMON KUROSE.
